F. CIESZKOWSKI,
BRUSH AND COMB CONSTRUCTION,
APPLICATION FILED MAR. 25, 1918.

1,277,858.

Patented Sept. 3, 1918.

UNITED STATES PATENT OFFICE.

FRANK CIESZKOWSKI, OF ROBYVILLE, OHIO.

BRUSH AND COMB CONSTRUCTION.

1,277,858.

Specification of Letters Patent. Patented Sept. 3, 1918.

Application filed March 25, 1918. Serial No. 224,513.

To all whom it may concern:

Be it known that I, FRANK CIESZKOWSKI, a citizen of Russia, residing at Robyville, in the county of Harrison and State of Ohio, 5 have invented certain new and useful Improvements in Brush and Comb Construction, of which the following is a specification.

The primary object of the invention is to 10 provide a brush and comb adapted for compact arrangement for convenience in traveling and readily positionable for use when desired in brushing and combing the hair.

A further object of the invention is the 15 provision of a hair brush arranged as a holder for a comb suitably encased therein when not in use but readily projected automatically for use in combing the hair whenever desired.

20 A still further object of the device is the provision of a combined hair brush and comb that is easy and inexpensive to manufacture and is sanitary in its arrangement, the comb being positioned out of sight when 25 not required for use and at which times the brush presents substantially the appearance of an ordinary hair brush.

In the drawings forming a part of this 30 application and in which like reference characters refer to corresponding parts throughout the several views,

Figure 1 is a central longitudinal sectional view taken through the device with the brush head shown in rear elevation.

35 Fig. 2 is a longitudinal sectional view thereof taken upon line II—II of Fig. 1.

Fig. 3 is a view similar to Fig. 1 with the comb projected for use and partially broken away.

40 Fig. 4 is a side elevation of the free end portion of the brush handle with the cap member indicated by dotted lines in its open arrangement, and

Figs. 5 and 6 are transverse sectional 45 views taken upon lines V—V and VI—VI respectively of Fig. 1.

Referring more in detail to the drawing the device broadly consists of a hair comb 10 of substantially the usual form adapted 50 for compact arrangement within a longitudinal chamber 11 of the handle 12 of a brush 13, the said comb being readily projected automatically in a position for use by the hereinafter described means.

55 The brush 13 includes a head portion 14

having a mirror 15 upon its rear face and with bristles 16 upon its opposite face.

The chamber 11 is rectangular in cross section being of a size adapted for the slide- 60 able reception of the comb 10 and the lugs 17 and 18 outwardly projecting from the opposite ends of the comb. A coil spring 19 is arranged within an axial bore 20 of the brush handle 12 normally arranged tensioned beneath the comb 10 within the portion 65 of the bore 20 arranged inwardly of the chamber 11 when the comb is in its inoperative inclosed position as shown in Figs. 1 and 2 of the drawing.

A socket 21 is arranged at the outer end 70 of the chamber 11 and bore 20 within the handle 12 having a swinging latch 22 pivoted therein as at 23 with a hooked end portion or foot 24 arranged overlying the lug 18 when the comb 10 is depressed and maintaining 75 the comb in its retracted position.

A spring 25 normally draws the foot 24 toward the plane of the lug 18 while a handle 26 of the latch 22 projects outwardly of the socket 21 for retracting the foot 24 off of the 80 lug 18. When the comb lug 18 is released in this manner, the spring 19 automatically projects the comb 10 in its position for use, it being understood however that the hinged cap 27 which is arranged upon the free end 85 of the handle 12 over the socket 21 has first been swung to its open arrangement.

A spring catch 28 is provided for normally maintaining the cap 27 closed and from this detailed description of the device, 90 it will be seen that when the device is closed as shown in Figs. 1 and 2 of the drawing, the catch 28 may be released and the cap 27 opened and thereupon the handle 26 may be moved for releasing the foot 24 from the 95 comb lug 18 so that the spring 19 will project the comb 20 to its open position as shown in Fig. 3. After the lug 18 is released from the foot 24, the spring 25 draws the foot 26 back to its position which will 100 be adjacent the comb back 29 so that the lug 17 of the comb 10 will contact the foot 24 when the comb is fully projected as shown in Fig. 3 of the drawing.

The comb may then be employed for use 105 upon the hair without detaching the same from the brush handle 12 although if desired, the latch 22 may be released from the lug 17, permitting the separation of the comb 10 from the handle 12 while the latch 110

22 will at all times overlie the outer end of the bore 20 sufficiently to prevent the accidental removal of the spring 19. The comb may be readily returned to its 5 closed arrangement by forcibly sliding the same inwardly of the chamber 11, compressing the spring 19 within the inner end of the bore 20 and laterally swinging the latch 22 to permit the lug 18 to pass behind 10 the latch which will then be returned to engage the said lug 18 and retain the comb within the brush handle 12.

The cap 27 is then closed and retained and 15 closed by means of the catch 28 until again manually released. A compact arrangement for a brush and comb is arranged serviceable for traveling and wherever it is ordinarily desired to have a comb with a brush or prevent the loss of a comb.

20 What I claim as new is:—

1. A device of the class described comprising a brush having a handle arranged with a chamber and an axial bore with a casing in the handle at the outer end of said chamber and bore, a closure cap for said socket, a coil spring within said bore, a comb engaging the said spring slidably arranged in said chamber, a retaining latch for said comb when retracted shiftably arranged 25 within said socket, an operating handle for said latch arranged outwardly of the brush handle, a lug upon one end of the comb adapted for engagement by the latch for maintaining the comb retracted and the lug 30 upon the opposite end of the comb adapted

for engagement by the latch for preventing the separation of the comb from the brush handle and a normally positioning spring for the said latch.

2. In combination with a brush having a chamber in the handle thereof, a comb arranged within said chamber when in its closed arrangement, an expulsion spring for the comb carried by said handle, a swinging latch upon the handle adapted for overlying the comb when retracted and a cap member normally arranged over the said latch and outer end of the comb upon the free end of the brush handle. 40

3. A device of the class described comprising a brush having a handle arranged with a chamber rectangular in cross section and with an axial bore traversing the said chamber, a comb fitted for sliding engagement within said chamber, an expulsion spring for the said comb arranged within said bore, means adapted for normally retaining the comb retracted adapted for preventing the separation of the comb and brush when the comb is in its projected operative positions, releasing means for the retaining means arranged exteriorly of the brush handle, normally positioning means for the retaining means provided within the brush handle, a swinging cap portion at the front end of the handle overlying the said retaining means when closed and a catch member for the said cap portion. 50

In testimony whereof I affix my signature.
FRANK CIESZKOWSKI,
